DRUM BEATER

Manny Goldrich, Hewlett, N. Y., assignor to
William D. Gladstone, New York, N. Y.

Application June 20, 1947, Serial No. 756,059

5 Claims. (Cl. 84—422)

1

This invention relates to musical instruments, and more particularly to wire brushes, sometimes referred to as jazz drum switches.

The wire brush is used with the drum or cymbal to obtain patten and swish-like sound effects. It comprises a tubular handle having at one end a plurality of thin gauge steel wires which spread out in the manner of a fan and are fastened to a clip or lug seated within and slideable along the length of the handle. For adjusting the spread of the wires, there is provided a metal rod which is fixedly connected at one end to the lug in the interior of the handle. The other end of the rod terminates in a loop or a ball located outside the handle to enable the rod to be easily grasped by the hand and moved along the longitudinal axis of the handle, thereby permitting adjustment of the effective length and the spread of the wires.

A difficulty experienced with known types of wire brushes is caused by undesired changes in adjustment of the wires during usage, due to inadvertent movement of the rod. This is due to the lack of means for locking the rod in different positions of use.

The present invention overcomes the foregoing difficulty.

According to the invention, the loop at the free end of the slideable rod is arranged to form a fastening element which cooperates with any selected one of several aligned holes in the tubular handle for fixedly positioning or locking the rod in a desired position, to thereby obtain a desired spread of the wires from the brush. The loop is slightly longer than the dimension necessary to form a one-turn fold, and the free end of the loop terminates in a drop pin which, due to the spring-like construction of the loop, may be arranged to fall into any one of several holes suitably aligned in the handle, in accordance with the wishes of the user. When the drop pin falls into a selected hole in the handle, the rod is relatively fixedly positioned on the handle until released by the user. It will thus be seen that the invention prevents inadvertent movement of the rod during usage of the brush.

A more detailed description of the invention follows in conjunction with a drawing wherein:

Figs. 1 and 2 show one embodiment of the invention, partially in section, with different adjustments of the locking device to obtain different spreads of the wires; and

Fig. 3 shows a modification of the locking device for the wire brush of the invention.

Referring to Figs. 1 and 2, there is shown a

2

wire brush or jazz drum switch comprising a tubular handle 10, preferably of elliptical cross-section; a plurality of fine quality, thin gauge, rust-proof piano steel wires 11 held together at one end by a metallic lug or clip 12; and an adjustment rod 13 having one end secured to the clip 12 and the other end terminating in a metallic loop 15.

The lug or clip 12 is crimped to hold the steel wires firmly and is slideable along the interior of the handle in response to movement of the rod 13.

The handle 10 essentially comprises a tubular sleeve which may be of any suitable material such as metal or plastic. If desired, the end of the sleeve farthest removed from loop 15 may be flared as shown.

The loop 15 is folded back upon itself and is provided with an extension piece 16. The end 20 of the extension piece 16 is bent to form a pin 17 which may be straight as shown in Figs. 1 and 2 or V-shaped as shown in Fig. 3. This pin is adapted to fall into any one of several spaced holes 18 arranged along a small portion of the 25 length of the handle preferably near the loop 15 as shown.

The construction of the metallic loop 15 is preferably such that it acts as a spring which normally exerts pressure on the pin 17 in a 30 direction toward the holes 18. These holes in the handle are sufficiently large to accommodate the pin. In order to release the pin 17 from any one hole in which it may be resting, it is only necessary to squeeze the loop, as a result of 35 which the extension 16 and pin 17 are drawn away from the handle 10 in a direction at right angles to the length of the handle.

When the pin 17 is in one of the holes 18, it acts to lock the rod 13 and wires 11 in a fixed 40 position which cannot be changed unless the pin 17 is raised and the loop 15 moved.

Fig. 1 shows the position of loop 15 for an 45 adjustment of minimum spread of the wires 11. It should be noted that the pin 17 is in the hole nearest the loop 15. Fig. 2 shows the position of loop 15 for an adjustment of maximum spread of the wires 11. In Fig. 2, the pin 17 is in the hole farthest away from loop 15. For positions of loop 15 intermediate those shown in Figs. 1 50 and 2, there will be intermediate adjustments of spread of the wires 11.

The spaced holes 18 in the handle 10 have been shown on a straight line and relatively few in number. It will be understood that this straight line arrangement is not essential in the

practice of the invention, particularly if the handle 10 has a circular cross-section, and that the spacing and number of holes may also vary as well as the length of extension 16. Further, although holes 18 have been shown in the handle, it will be apparent that these holes may be replaced by indentations which do not entirely penetrate the handle surface.

If desired, the handle 10 may be covered with a rubber sheath to furnish a better gripping surface for the fingers of the user, in which case the rubber sheath should have holes registering with the holes 18 in the handle so as to permit entry of the pin 17.

The term "depression" used in the appended claims is deemed to include a hole or a dent in the handle.

I claim:

1. A musical instrument comprising a wire brush having a tubular handle, a plurality of wires adapted to protrude from one end of the handle, a rod fastened to one end of said wires for adjusting the effective length and spread of the wires, said rod terminating in a loop externally of said handle at its other end, said loop having an extension adapted to extend over that end of the handle nearest said loop, said handle having spaced depressions into which the end of said extension may rest for locking said rod and wires in a selected position.

2. A musical instrument comprising a wire brush having a tubular handle, a plurality of wires adapted to protrude from one end of the handle, a rod fastened to one end of said wires for adjusting the effective length and spread of the wires, said rod terminating in a loop externally of said handle at its other end, said loop having an extension adapted to extend over that end of the handle nearest said loop, said handle having spaced depressions into which the end of said extension may rest for locking said rod and wires in a selected position, said loop being so constructed and arranged that it acts as a spring exerting pressure on said extension in a direction toward said depressions.

3. A musical instrument comprising a wire brush having a tubular handle, a plurality of wires adapted to protrude from one end of the handle, a rod fastened to one end of said wires for adjusting the effective length and spread of the wires, said rod terminating in a loop externally of said handle at its other end, said loop having an extension adapted to extend over

that end of the handle nearest said loop, said handle having holes spaced in a straight line along a portion of the handle nearest said loop into which the end of said extension may rest for locking said rod and wires in a selected position, said extension having an end bent at an angle to the extension, said loop being so constructed and arranged that it acts as a spring exerting pressure on said extension in a direction toward said holes.

4. A musical instrument comprising a wire brush having a tubular handle having spaced holes near one end thereof, a plurality of wires adapted to protrude from the other end of the handle, a rod fastened to one end of said wires in the interior of said handle for adjusting the effective length and spread of the wires, said rod terminating in a grasping surface located externally and at that end of the handle which is provided with said holes, and resilient means associated with said grasping surface and extending over the exterior of said handle, said resilient means being provided with an angular extension at its end for entering one of said holes.

5. A jazz drum switch having a tubular handle having openings at both ends and provided with spaced holes along a portion of the length thereof, a plurality of wires adapted to protrude from one end of said handle, and means for limiting the movement of said wires comprising a resilient wire member entering the other end of the handle and attached to said wires, said wire member having an end external of said handle bent at an angle and adapted to enter one of said holes.
